UNITED STATES PATENT OFFICE.

GEORGE E. STEVENS, OF LACONIA, NEW HAMPSHIRE.

KNITTING-MACHINE.

1,248,744.

Specification of Letters Patent. Patented Dec. 4, 1917.

Application filed October 12, 1914. Serial No. 866,215.

To all whom it may concern:

Be it known that I, GEORGE E. STEVENS, a citizen of the United States, residing at Laconia, county of Belknap, State of New Hampshire, have invented an Improvement in Knitting Machines, of which the following description, in connection with the accompanying drawing, is a specification, like characters on the drawing representing like parts.

This invention relates to dial knitting machines, and particularly to machines of this type which are provided with means for automatically forming a slack course or courses in the tubular fabric at predetermined intervals in the length thereof so that the fabric can be severed at the slack courses into lengths adapted to be used for the tops of half hose, cuffs for shirts, drawers, etc.

One convenient way of effecting the formation of the slack course above referred to in the operation of a knitting machine of the above type has been to provide means associated with the cam for operating the cylinder needles by which when the slack course is to be formed said needles are given an additional or extra vertical movement so as to produce longer loops, this being accomplished by providing the cam by which the cylinder needles are operated with a movable portion and providing suitable mechanism, usually pattern-controlled mechanism, to move said movable portion into a position to cause the cylinder needles to have an additional movement at such times as the slack course or courses are to be formed.

It has been proposed to provide means co-operating with the horizontal or dial needles by which the latter are elevated at the time that the vertical or cylinder needles are given their extra or downward movement, this upward or lifting movement of the dial needles co-operating with the extra downward movement of the cylinder needles to produce a slack course with enlarged loops.

It is a knitting machine of this latter class to which my invention particularly relates and the object of the invention is to provide a novel device for elevating the dial needles for the formation of the slack course, which

means will perform its duty without subjecting the dial needles to any strain tending to bend the dial needles out of their proper position or to otherwise injure them. In knitting machines of this type the needles which are used are small, delicate in their construction, and are easily injured or damaged if subjected to any violent force or strain. My invention provides a device for elevating the dial needles which can be used without injuring or affecting the operation of the most delicate needles.

In order to give an understanding of my invention I have illustrated in the drawings a selected embodiment thereof which will now be described, after which the novel features will be pointed out in the appended claims.

Referring to the drawings, Figure 1 is a side elevation of a portion of a knitting machine having my improvements applied thereto;

Fig. 2 is a partial sectional view on the line $x-x$, Fig. 1;

Figs. 3 and 4 are detail views through the dial-needle-elevating member taken on substantially the line $y-y$, Fig. 1, said views illustrating the operation of the invention.

The dial-knitting machine illustrated in the drawings comprises a frame or bed 1 carrying a needle cylinder 2 in which the vertical or cylinder needles operate, as usual, and also carrying a circular dial 3 in which the dial needles 40 operate. The vertical or cylinder needles are given their vertical or knitting movement by means of a cam carried by a cam ring 4 which is rotatively mounted on the frame, and the dial needles are given their knitting movement by means of a dial cam 5 which rotates with the cam ring 4, said dial cam 5 being herein shown as secured to a yoke or frame 6 which is rigid with the cam ring 4. The cam ring 4 is driven by any suitable or usual mechanism which, however, is not herein shown as it forms no part of the present invention. The cam ring 4 has associated therewith a movable cam member which is brought into play at the proper time to give the cylinder needles an extra downward movement for the formation of a slack course, this mov-

able cam member being herein actuated by a lever 7 pivoted at 8 to the cam ring and provided with a pin 9 which is adapted to be actuated by a pattern cam 10 mounted on 5 a rotary shaft 11 extending from the cam ring 4. This shaft is actuated to bring the cam 10 into operation periodically by means of a star-wheel 12 mounted thereon which at each rotation of the cam ring is engaged by 10 one or more pins carried by the frame 1. A dial-knitting machine having the above-described construction is well known to those skilled in the art and its operation need not be described in detail.

15 My present improvements relate to a novel device for lifting the dial needles at the same time that the lever 7 is actuated to give the cylinder needles their additional downward movement so that the slack 20 course is formed by the coöperation of the dial and cylinder needles. I accomplish this result herein by providing a freely-rotatable needle-lifting member which is normally out of engagement with the dial needles, 25 but which is brought into engagement therewith thereby to lift the same at the time that the lever 7 is actuated. The rotatable dial-lifting member which is in the form of a wheel will operate to give the successive 30 dial needles a gentle rise and fall which does not subject the needles to any severe strain, and by reason of the fact that the lifting member is rotatable, it will have a rolling instead of a sliding contact with the 35 dial needles, thus reducing friction and obviating any danger of bending the needles. This needle-lifting member is shown at 13 and it comprises a wheel which is rotatably mounted on a lever 14 that is pivotally connected to the rotating cam ring. In the 40 illustrated embodiment of my invention the cam ring 4 is provided with a bracket 16 to which the lever 14 is pivoted, as at 15. The lever 15 has associated therewith means 45 which is engaged by the pattern-actuated lever 7 when the latter is operated to produce the slack course whereby the lever 14 will be raised about its pivot thereby bringing the roll 13 into engagement with the 50 dial needles 40, as seen in Fig. 4, and raising the needles thereby to cause them to assist in the formation of the slack course.

In the illustrated embodiment of my invention the lever 14 is extended beyond the 55 roll 13, the extended end overlying the pin 9 by which the lever 7 is actuated, and this extended end of the lever 14 is provided with an adjustable screw 17 which is engaged by the pin 9 when the lever 7 is rocked 60 by the cam 10. With this construction it will be obvious that when the cam 10 has been actuated to operate the lever 7 thereby to cause the needle cylinders to have their extra vertical movement for the formation 65 of the slack course, such movement of the

lever 7 will actuate the lever 14 thereby bringing the roll 13 against the dial needles and elevating the latter, as seen in Fig. 4. This roll 13 has a rolling contact with the needle, and as it is carried around the dial 70 by the cam ring 4, the dial needles are successively raised slightly and then lowered again with an even motion due to the circular shape of the roll. Moreover, since the roll 13 has a rolling contact with the dial 75 needles instead of a sliding contact the engagement of the roll with the needles does not subject the latter to any lateral strain tending to bend them or otherwise injure them.

I have found from experiments that the construction herein illustrated is eminently practical for the purpose and that its use in a knitting machine does not affect in any way the operation of the knitting machine. 80

It is desirable that the roll 13 should be as large as practical in order to give the dial needles an easier rise and fall, and in order to permit the use of a comparatively large roll, I have placed the roll 13 at an angle 90 so that it rotates about an inclined axis. This permits the use of a larger roll than would be possible if the roll operated in a vertical plane about a strictly horizontal axis. The edge of the roll is preferably 95 beveled so that it will have a flat contact with the needles.

I claim:

1. In a knitting machine, the combination 100 with cylinder needles, of a rotary cam ring for operating them, dial needles, means for actuating said dial needles, a lever pivoted at one end to the cam ring, a roll mounted on said lever intermediate of its ends, a pattern-actuated lever pivoted to the cam ring, 105 and connections between said pattern-actuated lever and the first-named lever whereby the latter is raised by the former thereby to bring the roll into engagement with the dial needles.

2. In a knitting machine, the combination 110 with cylinder needles, of a rotary cam ring for operating them, dial needles, means for actuating said dial needles, a lever pivoted at one end to the cam ring, a bevel-faced 115 roll mounted on said lever to rotate about an axis inclined to the plane of the dial needles, a pattern-actuated lever pivoted to the cam ring, a pin extending therefrom, and a screw adjustably carried by the end 120 of said first-named lever and adapted to engage said pin whereby movement of the pattern-actuated lever will raise the first-named lever to bring the bevel face of said roll into engagement with the dial needles.

3. In a knitting machine, the combination 125 with cylinder needles, of a rotary cam ring for operating them, dial needles, means for actuating said dial needles, a lever pivoted at one end to the cam ring, a roll mounted 130

on said lever intermediate of its ends, a vertically-swinging pattern-actuated lever pivoted to the cam ring, and connections between said pattern-actuated lever and the 5 first-named lever whereby the latter is raised by the former thereby to bring the roll into engagement with the dial needles.

In testimony whereof, I have signed my name to this specification, in the presence of two subscribing witnesses.

GEORGE E. STEVENS.
